John G. Roberts

UNITED STATES PATENT OFFICE.

JOHN G. ROBERTS, OF DOBBS FERRY, NEW YORK, ASSIGNOR TO WESTERN ELECTRIC COMPANY, INCORPORATED, OF NEW YORK, N. Y., A CORPORATION OF NEW YORK.

CONTACT-BANK.

1,283,563.

Specification of Letters Patent.

Patented Nov. 5, 1918.

Application filed November 3, 1917. Serial No. 200,073.

To all whom it may concern:

Be it known that I, JOHN G. ROBERTS, a citizen of the United States, residing at Dobbs Ferry, in the county of Westchester 5 and State of New York, have invented certain new and useful Improvements in Contact-Banks, of which the following is a full, clear, concise, and exact description.

This invention relates to multiple contact 10 banks for electric switches of the kind having their brushes movable in two directions at right angles to each other.

The object of this invention in general is to provide a contact bank of this kind which 15 is so constructed that the brushes may travel a minimum distance in both directions to reach any one of the sets of contacts of the bank.

According to the general features of this 20 invention, there is provided a plurality of longitudinally extending wires grouped in sets with an equal number of sets divided in superimposed horizontal layers. These wires are insulated from each other by insulating 25 material formed into a practically solid structure except for openings running transversely in vertical and horizontal rows therethrough. Into these openings, brushes 30 may be passed to make contact successively with corresponding exposed contact surfaces of the wires in each set. More specifically two wires in each set, which normally are lying parallel to each other, are so bent and formed that portions thereof are exposed in 35 the bottom of said openings. The third wire which is straight lies between and slightly below the other two and is exposed through the roof of the opening below. Thus, it will be seen that the brushes must be arranged so 40 that two of them will pass through one opening and the other through the opening below to make contact with the sets in a layer. A brush operating mechanism may be provided, in front of each vertical row of 45 brushes for the manipulation of the brushes in two directions that is, upwardly in front of a vertical row of openings and horizontally through two adjacent openings in that row. A brush operating mechanism of this 50 type is shown in the pending application of John Newberry Reynolds, Serial No. 158,190.

In the drawings, Figure 1 is a perspective

view of a portion of the contact bank with parts broken away to show more clearly its 55 construction; Fig. 2 is a perspective view of one layer in the course of construction.

Referring to Fig. 1 of the drawing, 1 represents a complete bank built up of molded layers 2, in which the groups of wires 3, 4 60 and 5 are embedded with contact surfaces exposed at 6, 7 and 8 respectively. The brushes 10, 11 and 12 are shown in position to be moved into the openings 13 and 14, with the brushes 10 and 11 making contact 65 with exposed portions 6 and 7 of each set respectively, and brush 12 with exposed portions 8 of each set. A bank 1 built up by means of these layers 2 constitutes a structure in which are formed parallel vertical 70 rows of openings such as 13, 14 and 15.

The construction of a layer 2 is begun as shown in Fig. 2 in which a sheet or strip 16 of insulating material is stamped or molded with parallel transversely running grooves 75 18 on the upper side and similar grooves 19 on the lower side and with parallel longitudinally running grooves 20 on the upper side and 21 on the under side. The wires 3 and 4 are lying in two adjacent grooves 20 80 with their bent portions 6 and 7 resting on the upper surfaces 23 and 24 respectively, at the place where openings such as 13 and 14 and 15 are to be formed. The wires 5 are lying straight in the grooves 21 which are 85 of such depth as to allow the wires to be half exposed wherever they pass grooves 19. Each strip 16 with all the wires in place is then placed as a core in a form or mold which is shaped so as to allow a molten insulating compound to be poured around and embed the strip 16 and the wires with only, 90 the surfaces 6, 7 and 8 exposed. This mold is further shaped so that a lug 26, on the upper side and a lug 25 on the under side of the strip 16 are formed between every set 95 of contact surfaces 6, 7 and 8, as shown in Fig. 1. The insulating compound is of such character as to solidify when cold, and will therefore not only serve to hold the wires in place but also serve as a framework from which the complete bank may be built up, that is to say, when these layers 2 are piled on top of each other with the lugs 25 on one layer registering and resting on lugs 26 100 on the layer below, they will make up a bank 105.

as shown in Fig. 1 with the openings 13, 14 and 15 in proper relation to each other. The layers 2 may be held together by means of a suitable framework (not shown), thus giving to the bank a compact and substantial construction in which the wires are adequately protected from injury and accidental displacement.

The layers 2 are formed with wedge-shaped edges 27 so that the brushes will readily adjust themselves in the openings 13 and 14, thus allowing the mechanism that drives the brushes in a vertical direction to be of a less accurate adjustment and subject to considerable usage without imperiling its operation. This wedge-shaped edge 27 is especially useful as the distance between the layers 2 is relatively small.

One difficulty has been to arrange the wires in close proximity to each other and yet provide sufficient insulation between them and at the same time provide sufficient distance between the layers to permit of the free passage of the brushes without the possibility of having them come in contact with the wires of adjacent layers. The specific arrangement of the wires 3, 4 and 5 in relation to each other and the positioning of the exposed portions 6 and 7 of wires 3 and 4 in parallel straight lines and the alinement of corresponding wires 5 in the same vertical plane with these portions, makes it possible to build the layers 2 with their sets arranged specially close together. The distances between the corresponding wires in adjacent sets are by this arrangement of sufficient width to insure against the brushes bridging two adjacent wires even though considerable inaccuracy may exist in the mechanism for moving the brushes across their contact surfaces.

It is obvious that the invention could be modified, to include more or fewer conductors in each set to be traversed by corresponding brushes, without departing from the spirit thereof.

What is claimed is:

1. A contact bank for electric switches comprising a longitudinally extending group of wires arranged in sets of three, two wires in each set being bent so as to form alternate raised contact surfaces, corresponding surfaces in every set arranged in transverse rows, and insulating material molded around said group of wires to expose said contact surfaces and corresponding surfaces on the third wire to form parallel paths for contact brushes.

2. A contact bank for electric switches comprising superimposed layers of longitudinally extending groups of wires arranged in sets of three, two wires in each set being bent to form alternate raised contact surfaces, corresponding surfaces in every set

arranged in transverse line, and insulating material molded around said layers with transverse openings between the layers to expose said contact surfaces and corresponding surfaces on the third wires to form parallel paths for contact brushes.

3. A contact bank for electric switches comprising a longitudinally extending group of wires arranged in sets of three, two of said wires in each set having alternate bent portions turned so as to lie in the same longitudinal direction, the third wire lying between but slightly below the other two wires parallel with the bent portions thereof, the bent portions of corresponding wires in different sets forming transverse rows of contact surfaces, a structure of insulating material molded around said wires exposing the bent portions and corresponding portions of the third wires.

4. A contact bank for electric switches comprising superimposed layers of longitudinally extending groups of wires arranged in sets of three, a pair of said wires in each set having alternate bent portions turned so as to lie in the same longitudinal direction, the third wire lying between but slightly below the other two wires parallel with the bent portions thereof, the bent portions of corresponding wires in different sets arranged in transverse rows, a structure of insulating material molded around said layers with transverse openings between the layers to expose the bent portions and corresponding portions of the third wires.

5. A contact bank for electric switches comprising a plurality of longitudinally extending wires arranged in sets, said sets being grouped into superimposed horizontal layers, bent portions on corresponding wires in each set arranged in transverse rows, insulating material molded around said wires with transverse openings exposing said bent portions to form paths for contact brushes.

6. A contact bank for electric brushes comprising a plurality of longitudinally extending wires arranged in sets, said sets being grouped into superimposed horizontal layers, insulating material molded around said wires with transverse openings and exposing sections of said wires to form paths for contact brushes.

7. A multiple contact bank comprising sets of conducting wires molded in insulating material and having alternate exposed and unexposed sections, each set consisting of three or more wires running approximately parallel to each other and all in the same plane throughout their exposed portions but not all in the same plane throughout their unexposed portions.

8. A multiple contact bank comprising grooved strips of insulating material, wires having offset portions for contact surfaces

supported in said grooves, and insulating means for securing said wires in said grooves.

9. A multiple contact bank comprising 5 grooved strips of insulating material, wires having offset portions for contact surfaces supported in said grooves, and insulating

material molded into said grooves to secure said wires in said grooves.

In witness whereof I hereunto subscribe 10 my name this 30th day of October, A. D. 1917.

JOHN G. ROBERTS.
